UNITED STATES PATENT OFFICE.

HARRY E. GUYER, OF PHILADELPHIA, PENNSYLVANIA.

DESIGN FOR AN EYEGLASS-CASE.

SPECIFICATION forming part of Design No. 31,351, dated August 8, 1899.

Application filed June 23, 1899. Serial No. 721,644. Term of patent 7 years.

To all whom it may concern:

Be it known that I, HARRY E. GUYER, a citizen of the United States, residing in the city and county of Philadelphia, State of Pennsylvania, have invented and produced a new and original Design for an Eyeglass-Case, of which the following is a specification, reference being had to the accompanying drawings, forming part thereof.

10 The leading feature of my design for an eyeglass-case is a case having a body formed of a bulging front and cover and a crescent effect on said cover.

Figure 1 represents a perspective elevation 15 of an eyeglass-case embodying my design. Fig. 2 represents an end view thereof.

In the drawings, A designates an eyeglass-case consisting of the body B and cover C.

The body is composed of the bulging front D and the flat back E. The cover is bulging, in accordance with the bulge of the front D. The bottom edge F of the cover is curved upwardly, and a portion of said cover above said edge is bent outwardly, forming the curve G, which with the curved edge F produces the crescent effect H.

Having described my invention, what I claim as new, and desire to secure by Letters Patent, is—

The design for an eyeglass-case, substantially as shown and described.

HARRY E. GUYER.
